TRAVELING RECORDER

Paul F. K. Erbguth, 120 Station Road, Great Neck, N.Y.,
and George F. Hageman, 390 Lum Ave., Union, N.J.

Filed Mar. 18, 1958, Ser. No. 50,080

Term of patent 14 years

(Cl. D52—6)

Fig. 1

Fig. 2

Figure 1 is a front elevational view of a traveling recorder showing our new design;

Figure 2 is a side view thereof; and

Figure 3 is a perspective view taken at an angle and from the rear of the recorder.

We claim:

The ornamental design for a traveling recorder, substantially as shown.
